DESIGN FOR A GAME BOARD

Edward J. Wohlfeld, Indianapolis, Ind.

Application August 18, 1934, Serial No. 52,986

Term of patent 3½ years

To all whom it may concern:

Be it known that I, EDWARD J. WOHLFELD, a citizen of the United States, residing in the city of Indianapolis, county of Marion, and State of Indiana, have invented a new, original, and ornamental Design for Game Board, of which the following is a specification, reference being had to the accompanying drawing, forming part thereof.

In the drawing, Fig. 1 is a plan view of a game board, showing my new design; and Fig. 2 is a central longitudinal section of the same.

I claim:

The ornamental design for a game board, as shown.

EDWARD J. WOHLFELD.
